CLAIM

The ornamental design for a hand-held umbrella hub, as shown and described.

DESCRIPTION

FIG. 1 is a perspective view of a hand-held umbrella hub showing my new design;

FIG. 2 is a front view thereof, the back view is a mirror image thereof;

FIG. 3 is a left view thereof;

FIG. 4 is a right view thereof;

FIG. 5 is a top view thereof;

FIG. 6 is a bottom view thereof; and,

FIG. 7 is a perspective view thereof, shown in the environment of an umbrella.

The broken lines of FIG. 7 showing the umbrella depict environmental structure and form no part of the claimed design. The remainder of the broken lines shown in the drawings depict portions of the hand-held umbrella hub that form no part of the claimed design.
